UNITED STATES PATENT OFFICE

GEORGE T. JOHNSON AND HARRY W. STERTZBACH, OF COLUMBUS, OHIO, ASSIGNEES TO
THE BUCKEYE STEEL CASTINGS COMPANY, OF COLUMBUS, OHIO

BOLSTER

Application filed April 13, 1928. Serial No. 269,692.

This invention relates to the construction of heavy capacity cars of the type in which the bolster is within the body cavity. Bolsters of this type have heretofore consisted substantially of two trusses joined integrally at their inner ends by a member of rectangular form. The rectangular member, unless its entire web is a continuous or uninterrupted plate, or unless there are struts or braces extending between its diagonally opposite corners, does not successfully resist deformation in the plane of the rectangle when there is an unsymmetrical vertical loading condition imposed on the structure 10 as an entirety. It is the object of our invention, therefore, to overcome this difficulty and to produce a bolster of truss form throughout having the portion immediately over the center sill region of the car so arranged that diagonal elements are called upon to resist deformation in this part of the bolster when the body is not uniformly loaded or the rolling of the car causes the side bearings to come into action. The invention 20 is illustrated in the accompanying drawings and will be hereinafter fully described, the novel features being particularly defined in the appended claim.

In the drawings:—

Figure 1 is a fragmentary view partly in elevation and partly in section of a car body and bolster therein showing one embodiment of the invention;

Figure 2 is an elevation of a portion of a bolster showing a slight variation in the structure illustrated in Fig. 1;

Figures 3, 4 and 5 are elevations showing different embodiments of the invention;

Figure 6 is a fragmentary view of Fig. 5;

Figure 7 is an elevation of another embodiment of the invention;

Figure 8 is a fragmentary view of Fig. 7.

Referring particularly to Fig. 1, the numeral 1 designates the side of a car body consisting of metal plates having a reenforcing angle bar 2 secured along their upper edges and an angle bar 3 secured along their lower edges, the outer edges of the floor plates 4 being also secured to the angle bar 3 as shown 50 and as will be understood. The center of

the floor plates is supported by the center sill which consists essentially of a pair of parallel channel bars 5 and cover plate 6 secured thereon. The bolster 7 rests directly upon the floor plates with its ends against the two sides of the body and it is formed on both faces with lateral marginal flanges 8 through which rivets are fastened to secure it firmly to the car sides and floor. On the top of the bolster, at each end thereof, is a central longitudinal rib 9 to which is secured the lower end of a wing plate 10 which is also secured to the car side.

Primarily, the bolster is a central vertical web with lateral flanges on both faces at both top and bottom. The web, however, is not continuous or solid it having been found desirable to provide openings, such as 11, to minimize the effect of shifting of the load in the car, and to attain the desired strength. The bolster is of truss formation from end to end. The openings 11 are triangular in outline and the alternate triangles are relatively reversed. Around each side of the triangle reenforcing ribs or flanges 12 are formed on both faces of the central web of the bolster and midway the adjacent ribs or flanges bracing or strut members 13 are provided on the web, said members extending diagonally between the top and bottom flanges of the bolster.

It is to be particularly noted that, in the form shown in Fig. 1, one strut member extends upwardly and outwardly from a point over or near the side of the center sill to the top of the bolster while, near the end of the bolster, two of the strut members have their lower ends meeting at the bottom of the bolster, and, at this meeting point, the bolster is widened, as indicated at 14, to provide an ample surface for the attachment of a side bearing 15. The central opening, 16, through the bolster is an inverted truncated triangle with the web expanded vertically immediately over the junction of the adjacent strut with the bottom flange 8, as shown at 17.

The side bearing may be located near the side of the car body at the outer side of the truck wheels and this arrangement is shown in Fig. 1, or the side bearing may be located 10

at the inner side of the wheels, as shown at 18 in Fig. 2, in which event the widened portion of the bolster bottom is correspondingly shifted. Inasmuch as the side bearing is then located between two struts instead of at the junction thereof, a post 19 is provided over the side bearing and bisecting the triangle to effect the needed bracing. It will be understood, of course, that the bolster may have provision for both locations of the side bearings so that either or both may be used as needed.

In the form shown in Fig. 3, the truss elements are so proportioned that the innermost struts 20 rising inwardly from the side bearings meet the top of the bolster vertical of the respective sides of the center sill. The central struts 21 are provided each having its lower end on the bottom flange of the bolster in the vertical plane of one side of the center sill and its upper end joined to the top flange of the bolster in the vertical plane of the opposite side of the sill, the two struts intersecting in the central vertical plane of the sill, as at 22.

In Figure 4, the struts 24 are carried from points spaced from the sides of the sill upwardly and inwardly to meet the top flange of the bolster at a point 25 over the center of the sill. From this meeting point, a vertical strut 26 extends downwardly approximately half the height of the bolster where it branches into divergent struts 27 which meet the bottom bolster flange over the sides of the center sill. In the forms shown in both Fig. 3 and Fig. 4, openings 28 are formed through the bolster web between the central divergent strut members and openings 29 are formed at the outer sides of said members.

In the form shown in Figs. 5 and 6, the strut members 30 correspond to the members 24 in Fig. 4 and there is a vertical strut 31 corresponding to the member 26. The lower end of the strut 31 divides and forms the transverse diverging branches 32 as well as the longitudinal diverging branches 33 and a web 34 connects the diverging members.

The form shown in Figs. 7 and 8 differs from that shown in Figs. 5 and 6 in having the lower end of the vertical strut member 35 passed into a conical or bell-like web 36 of elliptical form at its base and the bottom of the bolster is widened as at 37, to correspond to said elliptical base. An elliptical opening 38 is formed through the bottom of the bolster, and within the bell the strut 35 terminates in a cruciform foot 39.

Having fully described our invention what we claim as new and desire to secure by Letters-Patent, is:—

In a car construction, an inside bolster of skeleton rectangular form, and having diagonal struts joining the top and bottom of the bolster, said struts extending in series from one end of the bolster to the other, the bolster

having a marginal flange and the struts having flanges merging into the marginal flange, some of said struts having their lower ends united with the bottom of the bolster at points immediately above the center sill of the car.

In testimony whereof, we have signed this specification.

GEORGE T. JOHNSON.
HARRY W. STERTZBACH.
